BAR SCREEN

Filed Dec. 26, 1929

UNITED STATES PATENT OFFICE

EDWIN R. SCHOFIELD AND RICHARD KRAMAROFF, OF PHILADELPHIA, PENNSYLVANIA

BAR SCREEN

Application filed December 26, 1929. Serial No. 416,609.

This invention relates to improvements in screen structures and cooperating rake mechanisms used therewith.

The primary object of this invention is the provision of an improved combination coarse and fine bar screen, particularly well adapted for the effective removal and fine screening of detritus from liquids.

A further object of this invention is the provision of an improved combination coarse and fine bar screen having an improved toothed comb or rake head structure operating thereover for simultaneously cleaning both the fine and coarse bars of the screen.

15 A further object of this invention is the provision of an improved coarse and fine bar screen structure which enables the collecting of minute detritus from flowing bodies of liquid, in such a relation that heavier objects 20 may only engage with the coarser screens to prevent damage to the fine bars.

A further object of this invention is the provision of a combination fine and coarse bar screen in which the parts are assembled 25 in a very durable, well braced, and easily accessible relation.

30 A further object of this invention is the provision of an improved segmental type of combination fine and coarse bar screen, in which the parts are so arranged as to give the screen great strength so that turbulent waters flowing therethrough will not be able to bend or distort the fine bars.

Other objects and advantages of this invention will be apparent during the course of the 35 following detailed description.

In the drawing, wherein for the purpose of illustration is shown only a preferred embodiment of the invention.

40 Figure 1 is a fragmentary plan view showing the relation of the bars of the improved screen with respect to an improved raking head of a movable rake structure.

Figure 2 is a vertical sectional view taken 45 through the improved screen, showing the

operative relation of a rake head of a movable screen therewith.

Figure 3 is a fragmentary sectional view showing the relation of details of the fine and coarse bar screen at a corner of the base 50 mounting thereof.

Figure 4 is an enlarged fragmentary sectional view showing a relative arrangement of the coarse and fine bars of the screen, in relation to an improved toothed or comb arrangement of a movable raking head which simultaneously cleans both the fine and coarse bars.

Figure 5 is a fragmentary sectional view taken at one of the supporting points of the 60 screen structure, showing the relation of coarse and fine bars, and the operative relation of an improved raking head.

In the drawing, wherein similar reference characters designate corresponding parts 65 throughout the several views, the letter A may generally designate the improved screen structure, over which an improved collecting or raking head B of a movable rake C may cooperate in a novel relationship.

The movable rake C may be of any approved type, such as set forth in our application, Serial No. 318,227, filed November 9, 1928, or our co-pending application, Serial No. 416,608, filed December 26, 1930, or it may 75 be of any other movable type which enables a raking comb, head, or collecting part to move over a screen for the removal of detritus or collections therefrom. Suffice to say that the rake C includes a supporting 80 beam 10 on the outer end of which a transversely arranged raking head, member, or collecting plate B is positioned, which is relatively broad, and over which ejecting means D may operate as more specifically detailed 85 in our applications above referred to.

The screen A preferably comprises a plurality of segmental shaped coarse flat metal bars 15, which may be of any approved thickness or width, and which in cross section are 90

substantially rectangular as shown in Figure 4. In lieu of being segmental they may be straight if the screen is to be of the plane type, or the screen bars may be shaped as desired, consistent with the shape that it is desired the screen in set-up relation shall have. The coarse bars 15, near the convex edges 17 thereof are apertured at 18, transversely, for receiving therethrough connecting and supporting bolts, shafts, or pins 19. These bolts or pins 19 are provided at intervals along the lengths of the coarse bars 15, and at the sides of the screen the bolts or supporting members 19 may be secured to the side coarse bars 15, as by countersunk rivet heads 21, shown in Figure 4, or in lieu thereof of a bolt and screw threaded connection may be provided, as desired. The screen is of considerable length and may be split up into sections, and the sections bolted together to provide a screen of any desired width. On the bolts or supports 19 between the coarse bars 15 of the screen, spacing sleeves 22 are provided, which hold the coarse bars 15 in predetermined spaced parallelism in the screen structure. These sleeves 22 are provided with slots 25 extending transversely therethrough and intersecting the passageways thereof through which the bolt pins extend, so as to expose a segmental portion of the bolt 19 in each of the slots 25 when the sleeves are slipped thereon, as can readily be seen from Figures 4 and 5 of the drawing.

The fine bars 30 of the screen structure are very appreciably thinner than the coarse bars 15, and intended to be so closely spaced that they will catch minute particles of detritus from a liquid body which is being screened. These bars 30 are very thin, preferably of metal, and they are of a width appreciably less than the width of the coarser bars 15. Due to the fineness of the bars 30, they cannot be made of one-piece lengths, the same as the coarser bars 15, since it is impractical not only from a manufacturing standpoint, but from a standpoint of support. Therefore, it is preferred to make the fine bars in a plurality of sections, with the ends of the sections supported on adjacent spaced sleeves 22 and on the bolts 19 received therethrough. Thus, as shown in Figure 2, the fine screens 30 comprise a plurality of sections 30, the ends of which increase in width, as better shown in Figure 5 at 30^a, and which are formed so that one edge 35 rests against the bottom of a slot 25 in the sleeve 22, and the end edge 36 thereof rests against a similar end edge of a next adjacent section 30^a of the fine screen. The division edges 36 of the sections constituting a fine bar are radially arranged with respect to the axis of the shaft 19, as more particularly shown in Figure 5. The sections 30^a are forced into their slots 25, and frictionally held therein, and of course they are supported at their ends due to the

notching at 41 where they fit over the supporting pins or bolts 19, as shown in Figure 5. The flow of liquid is in the direction shown in Figure 2, normally assisting in maintaining the fine bars in position.

The improved screen structure A is supported near the upper end thereof against a transverse beam 45, which at the ends thereof may be anchored in suitable side walls 46 of a channel through which the liquid is flowing, which is to be screened. This beam 45 may be of channel shaped section, and the web thereof may be suitably apertured, as shown in Figure 4, for receiving extensions 47 of certain of the sleeves 22, which may be bolted as at 48 to the beam 45, in order to hold the screen in position. At its lower end the screen rests on a suitable cementitious or other foundation 50, which may be suitably notched at 51 for receiving the lower ends of the coarse bars 15 therein. The foundation 50 may be similarly notched for the finer bars if desired.

The relation as to width, of the fine and coarse bars of the finished screen, is shown in Figure 4. It is to be noted that the ends 60 of the coarse bars project considerably beyond the ends 61 of the finer screen bars 30. It is to be seen that a large number of the fine bars may be placed in each of the spaces between adjacent coarser bars 15, and if desired the screen facing edges of the fine bars may be chisel edged, as may also the coarser bars if desired. It is readily understandable that solid particles which would ordinarily damage the finer screens will be caught against the forwardly projecting ends of the coarser bars, and will not contact against the finer bars; although the latter will function to collect the finer detritus passing through the spaces between the coarser bars 15.

The rake or collecting member B is formed in a novel toothed relation for simultaneously cleaning the spaces between both the coarse and fine bars of the screen. To this end, the collecting head B is provided with projecting portions 70, adapted to extend into the spaces between the projecting ends of the coarser bars 15, and each of these projecting portions 70 is furthermore provided with a plurality of fine teeth 72, shown in Figure 4 of the drawing, extending materially into the spaces between adjacent fine bars 30, for combing said spaces and collecting detritus and foreign deposits therefrom. The projections 72 may be pointed, if desired, to accomplish this purpose. It is to be noted that there is a close and intimate intermeshing of the projections and teeth of the movable raking head B in the spaces between the coarse and fine bars, so that a simultaneous cleaning of both the fine and coarse bars will take place during a raking action of the head B. The structure F, shown in Figure 2, comprises means for removing the detritus after

it is discharged from the collecting head B by the ejector D, as has been described in detail in my co-applications above mentioned.

Various changes in the shape, size, and arrangement of parts may be made to the form of invention herein shown and described, without departing from the spirit of the invention or the scope of the claims.

We claim:

10 1. A screen comprising a plurality of relatively coarse detritus collecting bars, means to support said bars in spaced relation, and a plurality of fine bars appreciably finer than the coarser bars protectively mounted in each of the spaces on the screen between the adjacent coarser bars.

20 2. A screen comprising a plurality of relatively coarse detritus collecting bars, means to support said bars in spaced relation, a plurality of fine bars appreciably finer than the coarser bars mounted in each of the spaces on the screen between the adjacent coarser bars, the detritus collecting edges of the coarser bars projecting in a protecting relation beyond the detritus collecting edges of the finer bars.

30 3. A screen comprising a plurality of relatively coarse detritus collecting bars, means to support said bars in spaced relation, fine bars appreciably finer than the coarser bars mounted in the spaces on the screen between the coarser bars, the detritus collecting edges of the coarser bars projecting in a protecting relation beyond the detritus collecting edges of the finer bars, and rake apparatus including a rake head provided with a toothed structure for simultaneously cleaning the detritus collecting edges of both the coarse and fine bars of the screen.

40 4. In a screen structure of the class described the combination of a plurality of coarse bars, means holding said bars in detritus collecting parallelism, and a plurality of parallel fine screen bars carried on said last mentioned means in a protected relation in each of the spaces between adjacent coarse bars of the screen.

50 5. A combination coarse and fine bar screen comprising a plurality of coarse bars, supporting means connecting and spacing said coarse bars, and sectional fine screen bars mounted in close multiple relation in each of the spaces between the coarse bars upon said means which mounts and spaces said coarse bars.

60 6. A screen of the class described having coarse bars, a transverse pin extending through said coarse bars, sleeves on the pin between said coarse bars to hold them in properly spaced relation, said sleeves having slots therein, and a plurality of fine bars supported in said slots in each of the spaces between adjacent coarse bars.

65 7. A screen of the class described having coarse bars, a transverse pin extending

through said coarse bars, sleeves on the pin between said coarse bars to hold them in properly spaced relation, said sleeves having slots therein, a plurality of fine bars supported in said slots in each of the spaces between adjacent coarse bars, the detritus collecting edges of the fine bars being spaced inwardly of the detritus collecting edges of the coarse bars.

70 8. In a segmental screen the combination of a plurality of arcuate coarse bars, transverse pins extending through the coarse bars at intervals therealong, spacer means properly spacing said coarse bars, and fine bars in the spaces between each of the adjacent coarse bars supported upon said pins.

75 9. In a segmental screen the combination of a plurality of arcuate coarse bars, transverse pins extending through the coarse bars at intervals therealong, spacer means properly spacing said coarse bars, fine bars in the spaces between each of the adjacent coarse bars supported upon said pins, each of said fine bars being sectional, with the ends of the sections resting on the pins.

80 10. In a screen the combination of a plurality of coarse screen bars, spacing sleeves between the bars, fine screen means, and means mounting said fine screen means upon said spacing sleeves in affixed relation in the spaces between adjacent coarse bars.

85 11. In a screen the combination of coarse screen bars, transverse pins extending through the coarse screen bars, spacing sleeves slipped on said pins and spacing the coarse bars from each other, the said sleeves having slots transversely therethrough in closely spaced relation intersecting the passageways therethrough through which the pins extend so that segments of the pins extend into each of said slots of the sleeve, and fine bars having portions extending into the slots of said sleeves between the coarse bars, said portions being notched to receive the segmental portions of the pins therein.

90 12. A screen comprising a plurality of relatively coarse detritus collecting bars mounted in spaced relation for the collection thereagainst of heavy detritus, and a plurality of finer bars appreciably finer than the coarser bars protectively mounted in each of the spaces of the screen between adjacent coarser bars with their detritus collecting edges set inwardly of the detritus collecting edges of the coarser bars for the collection of finer detritus which passes into the spaces between the coarser bars.

95 13. A screen comprising a plurality of relatively coarse detritus collecting bars mounted in spaced relation for the collection thereagainst of heavy detritus, a plurality of finer bars appreciably finer than the coarser bars protectively mounted in each of the spaces of the screen between adjacent coarser bars with their detritus collecting edges set in-
